UNITED STATES PATENT OFFICE.

MICHAEL RAY HILTY, OF COMANCHE, TEXAS.

AMUSEMENT DEVICE.

Application filed November 10, 1923. Serial No. 674,019.

To all whom it may concern:

Be it known that I, MICHAEL R. HILTY, a citizen of the United States, residing at Comanche, in the county of Comanche and 5 State of Texas, have invented certain new and useful Improvements in an Amusement Device, of which the following is a specification.

The present invention relates to amusement devices susceptible to use as an amusement for the home or at summer resorts and carnivals.

The primary object of this invention is the provision of an amusement device or game 15 whereby any number of persons may exercise their skill in trying to hit a target which will sound or otherwise indicate when the target has been hit.

Another object of this invention is the 20 provision of an amusement device or game which will test the skill of one's eye in throwing a ball or other missile at a target placed on the floor or positioned against a wall.

25 Another object of this invention is to provide an amusement device which may be manufactured at a very low cost and therefore placed on the market at a price which will be attractive to the purchaser.

30 Other objects and advantages will appear in the following detailed description, taken in connection with the accompanying drawings, wherein:

Figure 1 is a perspective view of the device.

Figure 2 is a transverse sectional view through the device, showing the relative position of the various parts.

Figure 3 is a fragmentary sectional view 40 taken on the line 3—3 of Figure 2 and looking in the direction of the arrows.

Figure 4 is a detail side elevation of the plunger.

In the drawings, wherein similar reference 45 characters designate corresponding parts throughout the several views, A designates a novel game or amusement device embodying my preferred construction and comprising a base or platform B having legs or spacing strips C secured to the inner face thereof; D a target in the form of a plunger; E a signal secured to the inner side of the platform B, and F a pivoted tapper adapted to strike the bell E when the plunger D is caused to move inwardly by reason of the

plunger D being struck as by a ball or other missile H.

The base B as in the example shown, may be made of wood of any desirable shape and thick enough so as to not give when struck with a ball or other missile. The outer face 60 10 of the base B is preferably smooth in order that the ball H will not glance to one side when the game is being played. A hole 11 is provided centrally of the base B for receiving the plunger D and allowing the same to move freely therein. In the example shown, strips C have been secured to the inner face 12 for spacing the base B and providing a recess 12' for receiving the bell 70 E and tapper F. It is to be understood that feet may be substituted for the strips C if so desired. A circle 13, preferably of a color different from that of the face 10 may be delineated or otherwise provided on the 75 base B co-axial with the target D.

The target D, having the tubular stem portion 14 which is adapted to slidably fit within the hole 11 is provided on its outer end with an enlargement or head 15. As 80 can be seen from the drawings, the inner end of the stem 14 rests on one free end of the pivoted tapper F and may be held from accidental withdrawal by a retaining pin 15'.

The signal E as in the example shown, 85 consists of a bell 16 which is mounted on the inner face 12 and within the recess 12' as by a screw 17. The bell is positioned so that when the target D moves inwardly, the tapper F will be caused to strike the bell and 90 signal that the target has been hit.

The tapper F may be pivotally mounted 95 on the face 12 as by the brackets 18 and pivot pin 19. A weight 20 formed on the arm 21 of the tapper F is adapted to normally urge the plunger outwardly and therefore return the target to a normal or set position without the necessity of hand resetting. It can be seen that when the target has been caused to move inwardly by reason 100 of a missile coming in contact therewith, the weight 20 will be caused to strike the bell 16 and then, due to its weight, will return the target to a set position.

Any number of persons may play the 105 game. The game may be one hundred or more and is preferably played with a solid rubber ball; the players standing at opposite sides of the device, say five feet and throwing the ball at the target. When one 110

strikes the target, he may be credited with ten and when striking within the colored ring may be credited with five. The person who first scores one hundred points is credited with winning the game.

Changes in detail may be made without departing from the spirit or scope of my invention; but,

I claim:

- 10 1. In an amusement device a platform, spacing strips secured to the under side of said platform and providing a recess below said platform, a bell mounted on the under face of said platform in said recess, a movable target extending vertically through the platform and adapted for reciprocatory motion, and a tapper pivotally secured intermediate its ends to the under face of the platform for striking the bell when said
- 15

movable target is caused to move down- 20 wardly when struck with a missile.

2. In an amusement device a platform, spacing strips secured to the inner side of said platform and providing a recess, a bell mounted on the inner face of said platform 25 in said recess, a movable target slidably mounted in a hole in said platform and extending past the inner and outer faces thereof, a head formed on the outer end of said target and spaced from the outer face of the platform, a tapper having its arm pivotally secured to the inner face of said platform, and a weight formed on one end of the tapper arm for returning the movable target to a set position after said target has been 30 caused to move inwardly by being struck with a missile.

MICHAEL RAY HILTY.
